UNITED STATES PATENT OFFICE.

ELMER J. HAVERLY, OF SAYRE, PENNSYLVANIA.

ROLLER-PIN FASTENING FOR WATCHES.

SPECIFICATION forming part of Letters Patent No. 639,698, dated December 19, 1899.

Application filed April 3, 1899. Serial No. 711,465. (No model.)

To all whom it may concern:

Be it known that I, ELMER J. HAVERLY, a citizen of the United States, residing at Sayre, in the county of Bradford and State of Pennsylvania, have invented a new and Improved 5 Roller-Pin Fastening for Watches, of which the following is a specification.

My invention relates to improvements in the manner of fastening certain jewels of a watch in their settings, and has to do more particularly with the fastening for the jewel roller-pin in the roller-table. Heretofore these jewel-pins have been fastened in their settings by cement. In time the cement works loose 15 and the watch is thrown out of kilter.

The object of this invention is to do away with the cement and provide a permanent and secure fastening. I accomplish this object by means of the device illustrated in the accompanying drawings, in which—

Figure 1 represents the under face of a roller-table having my improved fastening device applied thereto; Fig. 2, a medial cross-section of the same, and Fig. 3 the top face of 25 a roller-table having a different form of roller-pin from that shown in Fig. 1.

Similar letters refer to similar parts in the several views.

a represents the roller-table, perforated at 30 the center at *b* to receive the spindle or staff of the balance-wheel.

c is the jewel roller-pin. (Shown cylindrical in Fig. 1 and of segmental cross-section in Fig. 3.) The pin may also be square in cross-section or of any desirable form. It is set in a correspondingly-shaped socket in the roller-table, which it fits closely. One face of the roller-table is provided with an annular groove

or pocket *d*, the outer periphery of which is preferably beveled, as shown in Fig. 2, and 40 cuts the socket for the roller-pin diametrically, or nearly so. A divided ring *e*, having its outer periphery beveled to correspond with groove *d* and cut to embrace a portion of the pin *c*, is sprung into the groove. This spring- 45 ring presses against the foot of the roller-pin and securely locks it in place, the ring itself being held in the groove by its beveled contact with the outer periphery of the groove. Moreover, the roller-table is driven down 50 upon a shoulder on the staff, which shoulder overlaps the spring-ring and prevents it from getting loose by any possibility.

Having thus described my improvement, and without restricting myself to the precise 55 form and structure of the spring and pocket as herein shown and described, what I claim as my invention, and desire to secure by Letters Patent, is—

1. In combination, a roller-table provided 60 with a pocket in one of its faces and having a socket for the roller-pin intersected by said pocket, a jewel roller-pin, and a spring set in the pocket and abutting against the roller-pin.

2. In combination, a roller-table provided 65 with an annular groove in one of its faces and having a socket for the roller-pin intersected by said groove, a jewel roller-pin, and a divided ring sprung into the groove and abutting against the roller-pin.

In testimony whereof I have affixed my signature in presence of two witnesses.

ELMER J. HAVERLY.
